UNITED STATES PATENT OFFICE.

MALCOLM D. RIKER, OF DOVER, NEW JERSEY, ASSIGNOR TO MCKIERNAN-TERRY DRILL COMPANY, OF NEW YORK, N. Y., A CORPORATION OF NEW JERSEY.

LIFTING-JACK.

1,390,642.

Specification of Letters Patent. Patented Sept. 13, 1921.

Application filed October 23, 1919. Serial No. 332,709.

To all whom it may concern:

Be it known that I, MALCOLM D. RIKER, a citizen of the United States of America, and a resident of Dover, county of Morris, 5 and State of New Jersey, have invented certain new and useful Improvements in Lifting-Jacks, of which the following is a specification, reference being had to the accompanying drawing, forming a part thereof.

10 The present invention relates particularly to lifting jacks of the screw type and the objects of the invention are to provide a light, powerful, easily assembled and relatively inexpensive device of this character.

15 Briefly, the invention comprises a tubular post member mounted on a base and supporting a nut, a sleeve slidably engaged over said post and operated by a screw engaged with the nut, said tubular post and 20 sleeve members being constructed preferably of commercial cylindrical tubing having indented or flattened slidably engaging side portions and the post member having the lower indented end thereof welded in a substantially cylindrical seat provided in the 25 base member.

One feature of my invention consists in flattening or indenting the post member for its full length and in providing the nut, 30 which is seated in the upper end of said post member, with laterally outstanding portions projecting beyond the indented sides of the post so as to slidably engage and guide the cylindrical portion of the 35 surrounding sleeve member.

Another feature of the invention is a step having a base portion fitted to both the cylindrical and flattened lower end portion of the sleeve and preferably secured by being 40 welded to said sleeve.

Other features will appear as the specification proceeds.

In the accompanying drawings I have illustrated the invention embodied in one of 45 its practical and preferred forms, but would have it understood that modifications may be made in the construction without departure from the true spirit and scope of the invention.

50 In said drawing:

Figure 1 is a vertical sectional view of the jack.

Fig. 2 is a similar view, taken on a plane at right angles to the plane of Fig. 1.

55 Figs. 3, 4 and 5 are cross sectional views,

taken substantially on the planes of lines 3—3, 4—4 and 5—5 of Figs. 1 and 2.

7 designates the base of the jack which may be of cast or forged metal and which is shown in the present disclosure as provided with a substantially circular seat 8 in the upper face thereof.

9 designates a tubular post member preferably formed of commercial tubing initially of cylindrical shape and having the 60 opposite side portions thereof indented or flattened as indicated at 10 for substantially the full height of the post. This post is secured in the base by engaging it in the cylindrical seat and then fastening it as by welding, as indicated at 11. In making this weld the welding metal is flowed into the spaces left between the flattened sides of the tubing and the surrounding wall of the circular seat, as indicated at 12 to provide keys between the post and the base securing said parts together and positively holding them 75 against relative rotation.

The outer sleeve 13 is also preferably formed of commercial cylindrical tubing of 80 a size to slidably fit over the post tubing and this sleeve is formed with corresponding indentations or flattened portions 14 at the lower end thereof to slidably fit over the indented or flattened portions of the 85 post, said construction preventing relative rotation between the post and sleeve.

The sleeve carries a suitable lifting head 15 for engaging the object to be lifted.

Mounted in the upper end of the tubular 90 post is the nut block 16, said nut block being of novel construction in that it is shaped at its lower end to fit within the indented post member and is provided at its upper end with laterally outstanding portions 17, 95 projecting beyond the indented side portions of the post and completing the rounded contour of the post so as to form a guide for the outer sleeve member.

The sleeve is operated by a screw 18, which 100 is preferably of tubular construction, as indicated, said screw engaging the nut and provided, in this particular disclosure with a worm gear 19 engaged by a driving worm 20 journaled in the head portion of the jack. 105

The connection between the screw, the worm gear and the lifting head is of novel construction, involving a form of unitary joint between the screw, the gear and a plug member which connects with the head. 110

This feature is clearly disclosed in Figs. 1 and 2, and consists in seating the plug 21 in the upper end of the screw and in seating the worm gear over the upper end portion of the screw, said plug and worm gear having annular recesses 22, 23 formed in their adjacent peripheral portions to provide a gutter into which the upper reduced end portion 24 of the screw projects. After 10 assemblage in this fashion the parts are secured together by flowing a welding metal in this gutter, substantially as indicated. This provides an integral tie between the screw, the plug and the gear and constitutes 15 a permanent joint which is both simple and can be easily made. The plug has a seat in the lifting head, as indicated at 25 and a thrust bearing or washer 26 may be interposed between the upper face of the gear 20 and the under face of the lifting head.

The jack is usually provided with a step, such as indicated at 27, for engagement beneath low objects. The step shown is of 25 novel construction in that it is provided with a base portion or flange-wall 28 of partly cylindrical conformation to fit the cylindrical portion of the outer sleeve member and with rearwardly projecting angular extensions or lugs 29 engaging the flattened sides 30 of the sleeve. This step may be secured to the sleeve member by welding and the flange-wall construction disclosed provides a very firm connection for said step, said flange-wall serving to brace the step and 35 facilitate the securing of the step in place by positioning the step on the sleeve in the course of the welding operation.

The front partly cylindrical portion of the flange-wall may be extended vertically an 40 appreciable distance, as indicated and this, in connection with the rearwardly extending portion effectually braces the step in the direction of stress.

The present construction provides a jack 45 which is exceedingly powerful and which at the same time is relatively light in weight. The main parts are constructed of standard commercial tubing, which needs only to be flattened or indented in the manner disclosed. The device is readily assembled and the parts which are to be permanently secured are of such construction that they can 50 be readily fastened by welding.

Proper lubrication of the screw is effected 55 in my invention by providing an oil duct 30 extending down through the head of the jack, through the plug and through the wall of the hollow screw to the interior of the nut block. This provides for a direct 60 flow of oil to the screw thread portions. The passage in the plug may be enlarged to provide a cavity which may contain a suitable wick or packing for the lubricant.

For extra heavy work the jack may be reinforced by a lining 31 disposed within the

tubular post about the screw, and arranged to form a supplementary support for the nut block. This lining is shown as a section of cylindrical tubing of substantially the diameter of the flattened or indented portion of the post and disposed within the post resting upon the base at its lower end and providing at its upper end a bearing 70 for the lower portion of the nut block.

What I claim is:

1. A lifting jack comprising a base having a substantially circular seat, a tubular post having a substantially cylindrical lower end with indented sides engaged in said seat and welded to said base with welding metal 80 flowed into the spaces between the flattened sides of the post and the surrounding walls of the circular seat, a nut block supported in the upper end of the post, a sleeve slidably engaged over the post and a screw engaged with the nut block and connected with the sleeve aforesaid.

2. In a lifting jack, a base having a substantially circular seat, a tubular post member having indented side portions extending the full length of the same, said post being engaged at its lower end in the seat in the base and connected thereto by a welded joint including a filling of welding metal between the indented sides of the post and the surrounding walls of the seat, a nut block having a base portion seated in the upper end of the post and having outstanding portions projecting beyond the indented sides of the post, a sleeve engaged over the post and slidably fitting the laterally projecting portion of the nut and guided thereby, a screw engaged with the nut and connected to the sleeve and means for rotating said screw.

3. In a lifting jack, a base, a tubular post mounted thereon and having indented side portions extending to the upper end of the same, a nut having a base portion seated in the upper end of the post and a laterally outstanding portion projecting beyond the 110 indented side portions of the post, a sleeve slidably fitting over said outstanding portion of the nut and provided with indented side portions fitting the indented side portions of the post, a screw engaged in the nut and connected with the sleeve and means for rotating said screw.

4. In a lifting jack a base provided with a substantially circular seat, a post consisting of a section of commercial tubing having indentations in the sides thereof extending the full length of said section, said post being engaged at its lower end in the seat in the base and connected with said base by a welded joint including welding metal filled into the spaces between the indented side portions of the post and the surrounding wall of the circular seat, a sleeve of commercial tubing slightly larger than the first section of tubing and slidably engaged over 120 125 130

- the same, said sleeves having indented side portions at the lower end thereof slidingly fitting the indented side portions of the tubular post, a nut having a base portion seated in the upper end of the tubular post and a laterally outstanding portion projecting beyond the indented side portions of the post and slidingly engaged by the surrounding sleeve, a screw engaged in said nut and connected with the sleeve and means for rotating said nut. 50
5. In a lifting jack, the combination of a nut, a tubular screw engaged with said nut, a plug set in the upper end of said tubular screw, a gear engaged over the upper end of the screw, said gear and plug having recessed portions providing an annular gutter at the upper end of the screw and into which gutter said upper end of the screw projects and welding metal filled in said gutter and integrally uniting the screw with the plug and gear respectively. 55
6. In a lifting jack, the combination with a post and a substantially cylindrical sleeve 20 slidably engaged over the same and provided with indented side portions, of a step, means securing the step to the sleeve comprising lugs straddling the indented portions of the sleeve, and a flange extending from the step in engagement with the sleeve between the indented portions. 60
7. In a lifting jack, the combination with a sleeve and a step, of a pair of spaced lugs extending from the step, a flange-wall on the step between the roots of the lugs extending perpendicularly to the lugs and step, flat walls on the sleeve in engagement with the adjacent sides of the lugs, and an arcuate surface on the sleeve between the flat walls 25 in engagement with the flange-wall on the step. 65
8. In a lifting jack, the combination with a base having a post rising therefrom and a cylindrical sleeve telescoped over the post, the end of the sleeve adjacent the base being oblong in cross section, of a step having a plane surface adapted to rest on the base, said step having means straddling the narrow part of said oblong section, and a flange-wall extending from the base and in contact with the cylindrical surface of the sleeve. 70
9. In a lifting jack, a base, a tubular post mounted on the base, a nut seated in the upper end of said post, a sleeve within said post supported on the base at its lower end and engaging the lower end of the nut at its upper end, a sleeve slidably engaged over the post, a screw engaged with the nut and connected with said slidale sleeve, said screw extending down within the sleeve inside the post and provided with means for rotating the same. 75
10. In a lifting jack, a base, a tubular post mounted on said base and provided with indented side portions, a nut seated in the upper end of said post, a substantially cylindrical sleeve within the post substantially the diameter of said indented side portions of the post, said sleeve having a bearing on the base at its lower end and supporting the nut at its upper end, a screw engaged in the nut and extending down inside said sleeve, a sleeve slidably engaged over the tubular post and connected with the screw, and means for rotating said screw. 80
11. In a lifting jack, the combination of a tubular post, a nut supported thereby, a hollow screw engaging said nut, a plug seated in the upper end of said screw, a lifting head supported by said screw, said lifting head, plug and screw having an oil duct for supplying a lubricant directly to the engaging threads of the screw and nut, and means for turning the screw. 85
12. In a lifting jack, a tubular post, a nut supported thereby, a screw engaged in said nut and provided with a closed upper end, said closed upper end portion of the screw having an oil cavity therein and a duct extending out from said cavity to the threaded portion of said screw, and a lifting head supported by the screw, said lifting head having an opening into said oil cavity in the upper end of the screw. 90
- In witness whereof, I hereunto set my hand this 21st day of October, 1919.
- MALCOLM D. RIKER.
